UNITED STATES PATENT OFFICE.

WALTER N. THOMPSON, OF TAFT, CALIFORNIA, ASSIGNOR TO STANDARD OIL COMPANY, OF SAN FRANCISCO, CALIFORNIA, A CORPORATION OF CALIFORNIA.

ROTARY CORE DRILL.

Application filed July 28, 1925. Serial No. 46,630.

This invention relates to core drills for forming and removing a core from a hole being drilled in the earth, and is more particularly directed to a core drill of the rotary type adapted to secure a core from the formation in a single piece so that the stratum in the core will remain in proper position in relation to the adjacent strata.

Core barrels as now used are for the purpose of ascertaining the nature or composition of underground formations and are of such construction and manner of use that the core taken will not indicate the direction of tip and strike of the formation; as these prior core drills have no provision for preventing or determining the amount of rotation of the core during core cutting and removing operation.

In many prior types of core drill, core retainers have been employed which have vertical axial bores in the lower ends thereof which vertical bores, being of the same diameter as the central aperture between the cutting teeth, cause the core to bind at this point so that cores taken by these core drills are usually fractured in several places and each section of the core rotated through a different angle. It will be obvious that such a core would not show, or even indicate, the true relation of angles of dip and strike of the strata in the core.

An object of this invention is to produce a core drill adapted for taking cores by cutting the same from the formation in a single piece so that each stratum in the core will remain in proper relation to the adjacent strata so that the angles or dip and strike of the strata in the core may be determined when the core is raised to the surface at which time the amount of rotation of the drill pipe as it is withdrawn from the well is determined so that the core can be oriented to the position corresponding to its original position in the well.

Another object of this invention is to provide a core drill by means of which a core may be taken from underground formations and in which core drill means are provided for eliminating the source of friction between the core and the core drill so that on the draw of the core from the underground formation the core can be oriented to a position corresponding to its original position in the well.

Another object of this invention is to pro-

vide a core drill in which there is provided an inner barrel and means within the core drill by which the inner core-receiving barrel may be actuated to cut or break loose the core when the same has been taken from the underground formation.

Another object of this invention is to provide a core drill in which means are provided for cutting loose the core from the formation so that it is unnecessary to burn in the hole first as is now common practice.

Other objects and advantages of this invention will be apparent from the following detailed description of a preferred embodiment thereof as illustrated in the accompanying drawings.

In the drawings:

Fig. 1 is a vertical central section of an assembled core drill embodying this invention.

75

Fig. 2 is an enlarged fragmental vertical section of the core drill taken at 90° from Fig. 1, illustrating the jar construction embodied in this invention.

Fig. 3 is an enlarged central end elevation taken substantially on the line 3—3, of Fig. 1.

80

Fig. 4 is an enlarged sectional end elevation taken substantially on the line 4—4 of Fig. 1.

85

In the preferred embodiment of this invention illustrated in the accompanying drawings, 1 shows an outer barrel which may be constructed of heavy pipe or like material and which is threaded at its ends 90 with female threads 2 to receive male threads on a core cutting head or body 3, and male threads on the tool joint 4 by means of which the same is connected to the string of drill pipe. Loosely supported within the outer barrel 1 at the lower end thereof is a core-receiving shell 5 which is constructed of thin metal and which is slotted at its lower end as at 6, and which core-receiving shell 5 has a circumferential recess 6^a at the lower end 100 thereof to aid in the crimping of the said shell as will hereinafter appear. The circumferential recess 6^a provides a space 6^b which communicates with the longitudinal slots 6 formed in the lower end of the core 105 receiving shell 5.

Secured within the barrel 1 at a point above the core-receiving barrel 5 is a guide plate 7 which guide plate 7 has an interior bore 8 through which a stem 9 projects. A 110

- plurality of ports 10 are formed in the plate 7 so as to permit the free passage of flushing fluid into the space between the inner barrel 5 and the outer barrel 1. The stem 9 is secured to a head member 11 which head member 11 is rigidly secured to the upper end of the core-receiving barrel 5 and which head member 11 has a plurality of longitudinal flushing fluid ports 12 formed there-
 10 in which are for the purpose of establishing communication from the space between the barrels 1 and 5 and the interior of the barrel 5. The ports 12 communicate with a vertically extending port 13 in which port 13 a ball check valve 14 is mounted. Mounted within the upper end of the barrel 1 and screw threaded to the tool joint 4 is a sleeve 15 which sleeve 15 has a plurality of ports 16 formed therein through which the flush-
 20 ing fluid is permitted to pass from the interior bore 17 of the tool joint 4 and which sleeve 15 likewise has a plurality of ports 18 formed in its lower end to permit the discharge of the flushing fluid from within
 25 the sleeve 15. A mandrel 19 is screw threaded to the sleeve 15 as illustrated at 20 and extends upwardly approximately half of the length of the sleeve 15. A jar head 21 is guided within the mandrel 19 and is yield-
 30 ably supported within the sleeve 15 by means of a spring 22, which spring 22 encircles the mandrel 19 and engages the lower end of the sleeve 15 and engages at its upper end a washer 23 which is maintained in position
 35 by means of a nut 24 which is screw threaded to the head 21.
- Screw threaded to the lower end of the rod 22 and yieldably supported thereby, is a heavy weight 25 which heavy weight 25 is
 40 adapted to engage the upper end of the mandrel or stem 19 when the core drill is raised by the fluid string and dropped quickly. This dropping of the core drill causes the weight 25 to strike the stem 9, likewise caus-
 45 ing the inner barrel 5 to be jarred or ham-
 mered downward through the core drill head 3 which crimps the lower slotted end of the inner barrel 5 as will hereinafter be de-
 scribed.
- 50 The inner bore of the core head 3 is of reduced diameter at the lower cutting end 26 and is tapered rearwardly from this re-
 duced portion as illustrated at 27 to a diam-
 55 eter equal to the outer diameter of the core-
 receiving barrel 5. The lower end of the core-receiving barrel 5 therefore rests upon the tapered section 27 of the core drill head. Upon the core-receiving barrel 5 being forced downward by the hammer 25 strik-
 60 ing the stem 9, the lower slotted end of the core-receiving barrel 5 is crimped or bent inward along the slotted portion 27 of the core drill head or bit 3, which crimping of the lower end of the core-receiving barrel
 65 5 results in the cutting loose of the core
 from the formation. The core drill head 3 may be of any desired or preferred construction and is herein illustrated as includ-
 70 ing a plurality of outwardly diverging water ports 28 adapted to direct flushing fluid against the walls of the hole being cored and as including a plurality of radially op-
 posed cutters 29 and upon the lower end of which core drill head 3 a cutting surface 30 is formed. The head member 11 is remov-
 75 ably secured to the core-receiving barrel 5 by means of a pair of screw studs 31 which are screw threaded into the head member 11 when the same is inserted within the upper end of the core-receiving barrel 5 and which studs project outward from the head 11 into the L-slot formed in the upper end of the core-receiving barrel 5.
 80 The operation of this core barrel is as follows:
 85 The core barrel is rotated upon the formation until the desired length of core has been cut. The drill pipe and attached core barrel are then raised a few inches and then dropped upon the bottom of the hole, much after the manner of "spudding" a well. The jar which occurs when the cutting head 3 strikes the bottom of the well causes the weight 25 to descend, compressing the spring 22 and striking the driving pin 9 a sharp blow. This may be done one or more times as may be necessary. The driving pin 9 being attached to the core retainer shell 5 by means of the driving head 11, forces the core retainer shell 5 down into the downwardly reduced tapered bore 27 of the cutting head 3 causing said core retainer shell 5 to become crimped inwardly against the core which may be partially fractured by this operation. The core barrel is then pulled upward causing the core to be completely severed from the surrounding formation at the point of crimping. This crimp in the bottom of the core retainer shell also aids in preventing the escape of the core while the core or barrel is being drawn to the surface.
 90 It will readily be seen from the foregoing description that, after the core has been severed from the surrounding formation, there can be no rotation of the core with respect to the core barrel or drill pipe for the reason that the core is gripped tightly by the crimped core retainer shell which is it-
 95 self wedged tightly into the tapered bore of the cutting head 3. The cutting head 3, outer core barrel 1, and coupling 4 are all rigidly secured to the tubing string (not shown). Thus any rotation of the core which may occur while drawing the core barrel to the surface will necessarily be due to rotation of the entire tool string. Such rotation may be noted at the top of the well by marking the drill pipe in some suitable manner and observing the amount of rotation that has occurred. The re-
 100 105 110 115 120 125 130

covered core may then be oriented to correspond with its original position in the well and the direction of the dip and strike of the formations in the core will be in the same direction as the direction of the dip and strike of the subterranean formations from which the core was cut.

Having fully described a preferred embodiment of my invention, it is to be understood that I do not wish to be limited to the exact details herein set forth which may, obviously, be varied in detail without departing from the spirit of my invention as set forth in the appended claims.

15 I claim:

1. A rotary core barrel comprising an outer barrel carrying a cutting head on the lower end thereof, said cutting head having a downwardly reduced tapered bore, an inner core retaining shell vertically movable within said outer barrel, and means for driving said inner shell downwardly into the tapered bore of said cutting head, said driving means comprising a weighted plunger, and spring means mounted within the outer barrel above the said shell for yieldably suspending the weighted plunger above said inner core retaining shell.

2. A rotary core barrel comprising an outer barrel, a cutting head attached thereto and having an axial bore, cutting teeth disposed around said axial bore adapted to cut a core of smaller diameter than the said axial bore, an inner core retaining shell, a weighted plunger, spring means mounted within the said outer barrel and attached to the said weighted plunger so that when the said core barrel is dropped the said spring means is depressed to permit the weighted plunger to strike the end of the said shell and move the same into a tapered section of the cutting head to crimp the lower end thereof.

3. A core barrel comprising an outer core cutting barrel having a downwardly reduced axial bore therethrough, an inner core retaining barrel, and means for driving said inner barrel down into the reduced portion of the bore of said outer barrel, said inner barrel having a series of longitudinal slots in the lower end thereof and an annular channel in outer surface thereof communicating with said longitudinal slots and also communicating with the space formed between the walls of said inner and outer barrels.

4. A rotary core barrel comprising an outer core barrel, a cutting head secured to the

said core barrel at the lower end thereof, a core retaining shell mounted in the outer core barrel, a weighted plunger mounted in the core barrel above the upper end of the said shell, spring means mounted in position within the outer core barrel and secured to the said plunger and adapted to yieldably support the same, and means at the lower end of the said shell for crimping the same when the said core barrel is dropped to cause the said plunger to engage the said shell to move the same longitudinally of the said outer core barrel.

5. In a rotary core barrel, the combination of an outer core barrel, a core retaining shell mounted within the said outer core barrel, a weighted plunger, spring means yieldably supporting the said plunger, means for supporting the said spring means, said latter means having a fluid passage therein, and means at the lower end of the said core drill for crimping the end thereof when the said core barrel is dropped to move the said plunger against the spring pressure to cause the same to engage the said shell to move the same longitudinally within the said barrel.

6. In a rotary core barrel, the combination of an outer barrel, a core retaining shell slidably mounted within the said outer barrel, a weighted plunger, spring means for yieldably supporting the plunger within the barrel, means for mounting the said spring means within the said barrel, said means having a fluid passage therethrough, a head member secured at the upper end of the said shell and having a valved fluid passage formed therein, and a stem secured to the said head and adapted to be engaged by the plunger.

7. In a rotary core barrel, the combination of an outer core barrel, a core retaining shell mounted within the outer core barrel, a sleeve secured to the said core barrel at its upper end, a mandrel passing through the said sleeve at its lower end, a weighted plunger secured to the lower end of the said mandrel, a spring mounted on the said mandrel for yieldably supporting the said weighted plunger above the upper end of the said shell, and means for crimping the lower end of the said shell when the said plunger strikes the upper end thereof.

Signed at Bakersfield, California, this 17th day of July 1925.

WALTER N. THOMPSON.
